UNITED STATES PATENT OFFICE.

JOHN S. PARK AND JOHN W. GRAHAM, OF ROCKPORT, INDIANA.

GLAND.

SPECIFICATION forming part of Letters Patent No. 279,499, dated June 12, 1883.

Application filed April 25, 1883. (No model.)

To all whom it may concern:

Be it known that we, JOHN S. PARK and JOHN W. GRAHAM, of Rockport, in the county of Spencer and State of Indiana, have invented 5 certain new and useful Improvements in Glands; and we do hereby declare the following to be a full, clear, and exact description of the invention, such as will enable others skilled in the art to which it pertains to make 10 and use it, reference being had to the accompanying drawings, which form part of this specification.

Our invention relates to an improvement in glands; and it consists in a gland having a 15 chamber made at the outer end to receive cotton or other absorbent material, in combination with an oil-cup, which is placed on top of the gland and connected with the chamber, as will be more fully described hereinafter.

20 The object of our invention is to so construct a gland that it will lubricate the piston-rod, as it works back and forth through it, at all points alike.

Figure 1 is a vertical longitudinal section of 25 a gland embodying our invention. Fig. 2 is a front view of the same.

A represents the gland, which may either be of the construction here shown or any other that may be preferred, and which has the 30 chamber B formed in its outer end. This chamber is covered over by the removable cap C, so as to hold the cotton or other absorbent material which is placed therein in posi-

tion. Through the cover and the gland the piston-rod plays back and forth, and the absorbent material is packed in this chamber around the rod, as shown. Upon the top of the gland is placed an oil chamber or cup, D, which is secured in place in any-suitable manner, and down through the center of which 40 passes the grooved regulating-screw O. By the adjustment of the screw the amount of oil which is fed to the absorbent material can be regulated at will. All of the oil that flows from the cup into the chamber B is absorbed 45 by the cotton or other material, and as this material is in direct contact with the piston-rod the rod is lubricated at all points alike.

Having thus described our invention, we claim—

1. The combination of a gland with an oil-cup which is applied thereto, and a regulating screw or device, substantially as shown.

2. The combination of a gland having a chamber, B, formed in its outer end, the cap C, 55 an oil-cup, and the regulating-screw, the parts being arranged to operate substantially as set forth.

In testimony whereof we affix our signatures in presence of two witnesses.

JOHN S. PARK.
JOHN W. GRAHAM.
